(57) **CLAIM**

The ornamental design for a bottle for olive oil, as shown and described.

DESCRIPTION

FIG. 1 is a perspective view illustrating an embodiment of our new and ornamental design for a bottle for olive oil;

FIG. 2 is a top view illustrating the new and ornamental design for the bottle of FIG. 1;

FIG. 3 is a bottom view illustrating the new and ornamental design for the bottle of FIG. 1;

FIG. 4 is a back view illustrating the new and ornamental design for the bottle of FIG. 1;

FIG. 5 is a front view illustrating the new and ornamental design for the bottle of FIG. 1;

FIG. 6 is a right-side view illustrating the new and ornamental design for the bottle of FIG. 1;

FIG. 7 is a left-side view illustrating the new and ornamental design for the bottle of FIG. 1;

FIG. 8 is a perspective view illustrating yet another alternative embodiment of the new and ornamental design for the bottle of FIGS. 1-7, wherein the bottle comprises a transparent material;

FIG. 9 is a top view illustrating the new and ornamental design for the bottle of FIG. 8;

FIG. 10 is a bottom view illustrating the new and ornamental design for the bottle of FIG. 8;

FIG. 11 is a back view illustrating the new and ornamental design for the bottle of FIG. 8;

FIG. 12 is a front view illustrating the new and ornamental design for the bottle of FIG. 8;

FIG. 13 is a right-side view illustrating the new and ornamental design for the bottle of FIG. 8; and,

FIG. 14 is a left-side view illustrating the new and ornamental design for the bottle of FIG. 8.
